UNITED STATES PATENT OFFICE.

JOHN GODFREY PARRY THOMAS, OF CHISWICK, LONDON, ENGLAND.

SUSPENSION OF RAIL-CAR BODIES AND THE LIKE.

1,099,949.

Specification of Letters Patent. Patented June 16, 1914.

Application filed June 26, 1913. Serial No. 775,948.

To all whom it may concern:

Be it known that I, JOHN GODFREY PARRY THOMAS, a subject of the King of Great Britain, residing at 21 Ennismore avenue, 5 Chiswick, in the county of London, England, have invented new and useful Improvements in the Suspension of Rail-Car Bodies and the like, of which the following is a specification.

10 This invention relates to the suspension of rail vehicle bodies on bogies and has as its object the attainment of an efficient suspension with a cheap and light construction.

According to the invention levers which 15 at one end support the center plate of the vehicle body and at the other end the edge of the body, are pivoted upon the bogie main frame and springs are interposed between the center plate and these levers. Preferably the levers are so arranged that a tilting 20 of the vehicle body toward one side causes the center plate and the whole body to be shifted toward the opposite side, with the result that the weight tends to be evenly distributed between the two sides.

25 A preferred construction according to the invention is illustrated in the accompanying drawings in side elevation in Figure 1, in end elevation in Fig. 2, and in plan in Fig. 3, Figs. 2 and 3 being half views, and all 30 the views showing only so much of the vehicle as is necessary to make clear the nature of the invention.

In the accompanying drawings, 1 indicates the side members of the bogie frame supported upon springs on the wheel axles. These carry brackets 2 which support the pivots of bell crank levers 3. The outer ends of these levers 3 carry rollers 4 with 35 curved peripheries. The inner ends of the levers are joined through links 5 to the ends of a laminated spring 6. At its center there is secured to this spring a socket plate 7 which in fact constitutes the bogie bolster. 40 This has a spherical bearing surface to receive a pivot pin 8 which may be called the king pivot and which is attached to the body bolster or main frame 9. This main frame has at its edges bearing plates 10 in position 45 to contact with the rollers 4.

50 It will be understood that the weight of the vehicle is divided between the socket plate 7 and the two rollers 4 according to the dimensions of the levers. By suitable de-

sign, therefore, the spring 6 may be caused 55 to support only a small proportion of the total weight of the coach. If the vehicle in rounding a curve should tend to cant toward one side, say toward the left, the roller 4 on that side will be depressed and the lever 3 60 will rotate a little. On the opposite side the roller can rise and the lever 3 can rotate in the opposite direction. The result of these movements it will be seen is to move the whole spring 6, the socket plate 7, the 65 king pivot 8, and the whole vehicle frame 9 toward the right, thus bringing a greater proportion of the weight upon the right hand roller 4 and tending to restore the body to its horizontal position.

70 It will be obvious that the design of the levers 3 may be varied; for example the levers could be straight instead of being bell crank levers. In this case, however, unless the levers are inclined there would be no 75 tendency to move the vehicle bodily to the right when it tilted to the left; but the distribution of weight between the pivot pin and the side rollers would be secured just as in the construction described. An ordinary standard king pin and center plate may be used instead of the spherical pin and socket referred to above. It is evident also that the positions of the spherical pin and the socket might very conveniently be reversed so that the former instead of the latter forms part of the bogie bolster. Finally, the laminated springs might be replaced by a beam supported on the links and carrying a number of suitable springs which 80 would in turn support the spherical pin or socket plate.

85 What I claim is:

1. In a bogie vehicle the combination with the bogie main frame of levers pivoted thereon transverse to the vehicle, a main frame resting on one end of said levers and a resilient support interposed between said main frame and the other end of said levers.

2. In a bogie vehicle the combination with the bogie main frame of levers pivoted thereon carrying rollers at their outer ends, a vehicle body resting in part on said levers and a pivotal support at the center of said body resting resiliently on the inner end of 100 said levers.

3. In a bogie vehicle the combination with the bogie main frame of levers pivoted

thereon having inclined arms, a vehicle body resting in part on one end of said levers and a resilient support at the center of said body resting upon the ends of the inclined arms of said levers.

4. In a bogie vehicle the combination with a bogie main frame of levers pivoted thereon, links depending from the inner end of said levers, a spring connecting and resting on said links, and a main vehicle body resting in part on said spring and in part upon the outer ends of said levers.

5. In a bogie vehicle the combination with a bogie main frame of levers pivoted thereon having inclined inner arms, links depending from the inner end of said levers, a spring connecting and resting on said links, and a main vehicle body resting in

part on said spring and in part upon the outer ends of said levers.

6. In a bogie vehicle the combination with a bogie main frame of levers pivoted thereon, links depending from the inner end of said levers, a spring connecting and resting on said links and a pivoted support for said vehicle body resting on said spring, and a main vehicle body resting in part on said spring and in part upon the outer ends of said levers.

In testimony whereof I have signed my name to this specification in the presence of two subscribing witnesses.

JOHN GODFREY PARRY THOMAS.
